SPOON OR SIMILAR ARTICLE

William L. Lafferty, Providence, R. I., assignor to
Reed and Barton, Taunton, Mass., a corpora-
tion of Massachusetts

Application December 13, 1949, Serial No. 6,597

Term of patent 14 years

(Cl. D54—12)

To all whom it may concern:

Be it known that I, William L. Lafferty, a citizen of the United States, residing at Providence, in the county of Providence and the State of Rhode Island, have invented a new, original, and ornamental Design for a Spoon or Similar Article, of which the following is a specification, reference being had to the accompanying drawing, forming a part hereof.

In the drawings:

Figure 1 is a front elevational view of a spoon embodying my new design,

Figure 2 is an enlarged cross-sectional view taken on line 2—2 of Figure 1,

Figure 3 is an enlarged cross-sectional view taken on line 3—3 of Figure 1, and

Figure 4 is a rear elevational view of said spoon.

I claim:

The ornamental design for a spoon or similar article, as shown.

WILLIAM L. LAFFERTY.
